OUTRIGGER ROD

Julian T. Crandall, Ashaway, R. I., assignor to
Ashaway Line & Twine Mfg. Co., a corpora-
tion of Rhode Island

Application August 1, 1946, Serial No. 687,585

2 Claims. (Cl. 43—18)

1

My present invention relates to outrigger rods, and has particular reference to a novel construction for providing strengthening and an increased resilience.

The principal object of the invention is to provide an outrigger rod with a resilient strengthening against bending strains.

Another object of the invention is to provide a resilient strengthening which will not interfere with or otherwise affect the desired movement of the outrigger rod.

Still another object of the invention is to provide a resilient strengthening arrangement which can be readily attached to any outrigger rod.

A further object is to provide a resilient strengthening arrangement for an outrigger rod which may be economically manufactured.

With the above and other objects and advantageous features in view, the invention consists of a novel arrangement of parts more fully disclosed in the detailed description following, in conjunction with the accompanying drawings, and more specifically defined in the claims appended thereto.

In the drawings:

Fig. 1 is a view of an outrigger rod of standard type and of rectangular cross-section, equipped with the novel resilient strengthening arrangement;

Fig. 2 is an enlarged section on the line 2—2 of Fig. 1; and

Fig. 3 is a view similar to Fig. 2, showing a modified construction suitable for a round outrigger rod.

It has been found desirable to provide an outrigger rod with a resilient strengthening arrangement so that it will be strengthened for heavy fishing, without unduly increasing the weight, and without sacrificing any resilience. To this end, I have provided a guy wire arrangement which has novel supports for attaching to any standard type outrigger rod, and which has a plurality of spaced strengthening wires that may be individually adjusted so that the outrigger rod is strengthened to a desired degree in all directions of bending, while increasing the total resilience so that bending strains in the outrigger rod are reduced.

Referring to the drawings, the outrigger rod 10 is of standard hollow type, of rectangular or square cross-section, and has a butt end 11 which is slotted as indicated at 12 to seat in a base (not shown) of standard type, the rod being tapered to its tip 13. I provide a plurality of supports 14a, 14b, 14c, 14d, 14e, and 14f, hav-

2

ing bases 15a, 15b, 15c, 15d, 15e, and 15f of metal or the like adapted to snugly seat on the rod over bushings 16 of rubber or the like, the bases being progressively smaller, as illustrated.

5 The bases respectively have wire supports 17a, 17b, 17c, 17d, 17e and 17f mounted therein, preferably of heavy wire or rod construction, each support having a plurality of spaced sections 18 which have terminal eyes 19, each section also 10 having lugs in the form of rings 20 spaced at the sides of and below the terminal eyes 19. Strengthening wires 21 join the lugs or rings 20 to provide rigid supports of light weight, whereby guy wires 22 may be threaded through 15 the eyes 19 of the respective supports, as illustrated. The guy wires are secured to a metal cap 23 at their upper ends which is mounted on the rod tip and secured in place by any suitable means, such as a screw 24, and have turnbuckles 20 25 at their lower ends which are locked to support screws 26 or the like secured to the butt end 11 of the rod.

It is preferred to form the supports 17 of different sizes, as illustrated, the lowermost or butt end support 17a being smaller than the next support 17b, and the other supports being successively smaller, whereby the guy wires assume the shape illustrated in Fig. 1 and thus provide the desired strengthening at the butt end of the rod, while increasing the resilience of the tip end of the rod.

If desired, the supports may be made adjustable for circular rods by forming as indicated by numeral 27 in Fig. 3, wherein the base 28 is 35 round, and is formed of two hingedly connected portions 29, 30 which seat around a bushing 31 and respectively have terminal flanges 32, 33 adapted to be secured together by a manually turnable lock screw 34. This type of base will 40 fit a wide range of circular rod sections, and is suitable for application to existing rods, whereas the square type of base shown in Fig. 2 is more suitable for production manufacture as a unit with the rod.

45 The adjustable type of support shown in Fig. 3 is preferably provided with form spaced bars 35 each having a terminal eye 36, and the bars are preferably joined at their outer ends by a wire or the like 37 which is locked to each 50 bar as illustrated, whereby the guy wires passing through the terminal eyes 36 of the spaced supports are preferably supported therein.

Although I have described specific constructional embodiments of my invention, it is obvious that changes in the size, shape, material

and arrangement of the parts may be made to suit different strengthening requirements, without departing from the spirit and the scope of the invention as defined in the appended claims.

I claim:

1. In combination, an outrigger rod, spaced supports on said rod comprising bases mounted along the length of the rod, a resilient bushing positioned between each base and the contiguous rod portion each base having spaced sections extending therefrom, said sections having elements to slidably receive guy wires, and guy wires secured to the upper and lower ends of the rod and slidably seated in said section elements.

2. In combination, an outrigger rod, spaced supports on said rod comprising bases mounted along the length of the rod, a resilient bushing positioned between each base and the contiguous

rod portion each base having spaced sections extending therefrom, said sections having terminal eyes to slidably receive guy wires, and guy wires secured to the upper and lower ends of the rod and slidably seated in said terminal eyes.

JULIAN T. CRANDALL.
